UNITED STATES PATENT OFFICE.

CALVIN A. ELY, OF MOUNT VERNON, ILLINOIS.

COMBINATION RULE AND TRY-SQUARE.

No. 893,061.

Specification of Letters Patent.

Patented July 14, 1908.

Application filed January 16, 1908. Serial No. 411,108.

To all whom it may concern:

Be it known that I, CALVIN A. ELY, a citizen of the United States, residing at Mount Vernon, in the county of Jefferson and State 5 of Illinois, have invented a new and useful Combination Rule and Try-Square, of which the following is a specification.

This invention has relation to combined rules and try squares and it consists in the 10 novel construction and arrangement of its parts as hereinafter shown and described.

The object of the invention is to provide a rule having hinged sections with a means for holding said sections at a right angle to each 15 other whereby the rule may be used in the capacity of a square. The said holding means is so arranged upon one of the sections of the rule as to lie completely within the perimeter of the same when not in use and 20 therefore presents no obstruction to the free use of the rule. The parts of the holding means are also so arranged that they do not project laterally beyond the sides of the rule when used for holding the sections of the rule 25 at an angle, consequently, when used as a square the rule may lie flat at either side upon the work without obstruction on the part of the said holding means.

In the accompanying drawing: Figure 1 is 30 a side elevation of one form of rule showing the holding means applied thereto. Fig. 2 is a side elevation of another form of rule showing the holding means applied thereto. Fig. 3 is a detailed perspective view of the holding 35 means detached, and Fig. 4 is a transverse sectional view of a rule section showing a modified form of holding means applied thereto.

The rule 1 may be of any design of carpenter's rule generally known as a foot or two foot rule with sections hinged together as at 40 2. One of the sections is provided with an elongated groove 3 cut in its inner edge and the other section is provided with a recess 4 cut in its inner edge. The pin 5 passes transversely through the recess 4 and the bar or holder 6 is pivotally mounted at one end in the inner end of the groove 3. The bar 6 is provided at its opposite end with a notch 7 45 which is adapted to receive the pin 4. The bar 6 is adapted to lie in the groove 3 and

when in such position has one edge which is flush with the inner edge of the rule section containing the said groove. The inner edge of the bar 6 is provided with a thumb lug 8 by 55 means of which the said bar may be swung upon its pivot. The rule section having the groove 3 is provided at its edge with a recess 9 which is adapted to receive the thumb lug 8 and when the said lug is in the 60 said recess its outer surfaces lie in the same plane as the surfaces of the rule section. The thumb lug as shown in Fig. 3 extends to one side of the bar 6 only while the lug 8 as shown in Fig. 4 extends or lies upon the opposite 65 sides of the bar 6. Thus, the bar as shown in Fig. 4 may be opened by inserting the thumb nail under the lug 8 at either side of the rule section. When it is desired to hold the sections of the rule 1 at a right angle to each 70 other the bar 6 is swung upon its pivot and the free end of said bar is inserted in the recess 4 and the notch 7 is engaged upon the pin 5. Thus, the adjacent sections of the rule are held at a right angle while the said 75 bar lies at an angle of 45 degrees with relation to the rule section. Thus, the bar may be used for indicating such an angle upon the work.

It will be observed that when the bar 6 is 80 within the groove 3 it lies entirely within the perimeter of the rule section containing the said groove and consequently, does not interfere with the use of a rule as a straight edge, also when the bar is swung into engagement with the adjacent rule section that no 85 parts of the bar or its attachments project laterally beyond the planes occupied by the sides of the rule sections.

Having thus described my invention, what 90 I claim as new and desire to secure by Letters Patent is:

In combination a rule having hinged sections adapted to lie in contact when folded, one of said sections having a longitudinal 95 groove in the center of its inner edge and a short shallow recess in the same edge leading from said groove to the side of the rule, the other section provided in its inner edge with a deep recess and a pin extending transversely 100 across said recess; a thin flat bar pivoted at one end in one end of said groove and formed

with a notch in its other end to engage with the pin in the deep recess and hold the two rule sections firmly at a right angle to each other and the flat bar at an angle of forty-five degrees, said bar having a short thumb lug fitting said shallow recess when the bar is folded into the groove.

In testimony that I claim the foregoing as my own, I have hereto affixed my signature in the presence of two witnesses.

CALVIN A. ELY.
